UNITED STATES PATENT OFFICE.

FRANKLIN FORD PETERS, OF WINNIPEG, MANITOBA, CANADA.

MATCH-STRIKER.

1,292,035.

Specification of Letters Patent.

Patented Jan. 21, 1919.

Application filed April 3, 1918. Serial No. 226,485.

To all whom it may concern:

Be it known that I, FRANKLIN FORD PETERS, of the city of Winnipeg, in the Province of Manitoba, Canada, have invented certain new and useful Improvements in Match-Strikers, of which the following is the specification.

The invention relates to improvements in match strikers and the principal object of 10 the invention is to provide a simply constructed and inexpensive match striker arranged so that it can be conveniently secured in a non-conspicuous place to the clothes and which can be relied on to ignite 15 the match and without disfiguring in any way the garment.

A further object of the invention is to arrange the fastening pin so that when once fastened it will remain fastened and a still 20 further object is to construct the device from as few parts as possible without impairing its efficiency.

With the above objects in view the invention consists essentially in a striking plate 25 having a lengthwise extending channel or depression therein presenting a roughened face and fitted at the top end with a pair of guides and an indent and at the lower end with a pair of pockets and a pin passing normally through the guides and entering the 30 pockets, the parts being arranged and constructed as hereinafter more particularly described and later pointed out in the appended claim, reference being had to the accompanying drawing in which:—

Figure 1 represents a face view of the striker as it appears fastened to the interior face of a coat.

Fig. 2 represents an enlarged face view 40 of the striker.

Fig. 3 represents a reverse view of the striker with the pin shown withdrawn in dotted outline.

Fig. 4 represents a longitudinal sectional 45 view through the striker.

Fig. 5 represents an enlarged detailed horizontal sectional view through the striker and looking upwardly, the section being taken in the plane denoted by the line 50 X—X' Fig. 2.

Fig. 6 represents a horizontal sectional view through the striker, the section being taken in the plane denoted by the line 55 Y—Y' Fig. 2 and looking downwardly.

Fig. 7 represents a horizontal sectional view through the striker, the section being

taken in the plane denoted by the line Z—Z' Fig. 2 and looking downwardly.

In the drawing like characters of reference indicate corresponding parts in the 60 several figures.

1 represents a body of the striker which is made preferably from a metallic plate considerably longer than wide and which has the central portion thereof formed with 65 a lengthwise extending groove 2 made by depressing the plate to form the groove.

The front face of the groove is roughened to present a good striking face, such being done in the present instance by cross cutting 70 the face of the plate in the groove as indicated at 3 to present a rough surface, it being understood that the cuts do not go through the material of the plate. Directly above the upper end of the groove I form 75 a pair of guides 4 and 5 which are made by cross cutting the plate with pairs of parallel cuts which provide cross straps 6 and 7 which, after being formed, are pressed back to form, with the body of the plate, eyes 80 8 and 9.

Directly beneath the lower end of the groove 2 I provide on the rear side of the plate a pair of vertically disposed pockets 10 and 11 which are alined vertically with 85 the guides 4 and 5. These pockets are actually constructed by making two horizontally alined but spaced cross cuts 12 and 13 in the body of the plate and then depressing those portions of the plate beneath the cross 90 cuts backwardly and shaping the depressions so that they taper in a more or less half cone-shaped manner.

14 represents a fastening pin presenting a head 15 and two parallel pointed prongs 16 95 and 17. Normally the pin takes the position at the back of the plate with the head closed against the guides, the prongs extending through the guides and the points 16' and 17' of the prongs in the pockets.

In the upper end of the plate in a location centrally thereof and directly above the head of the pin I make a small hump 18 in the plate by indenting it which hump acts as a stop to prevent the pin from raising 105 sufficiently high to release the points from the pockets. It, however, is not of such magnitude that it cannot be forcibly drawn over the hump when one wishes to remove the striker.

In actual practice I have found it very advantageous to secure this striker on the

inner side of a coat front, as indicated at 19, so that one, by slightly opening his coat, can readily strike a match. Further by placing it in this position it is non-conspicuous 5 and the coat front acts as a windshield to protect the ignited match.

To attach the striker one withdraws the pin to a position such as shown in dotted 10 outline and places the plate with the rear side against the garment. The pin is then forced down so that the prongs will pass through and catch the cloth of the garment and finally take a position with the points in the pockets.

15 In this final position the location of the pin is as shown in the drawing and obviously the striker will be held to the garment by the prongs which pass through it. Any tendency for the pin to work loose is 20 counter-acted by the stop but if one wishes to remove the striker he has only to catch the head of the pin and pull it upwardly and forcibly over the indent.

From the above it will be apparent that 25 this device can be constructed at small cost and forms a convenient device for striking a match, the lighting of the match being accomplished by drawing the head of it

quickly over the roughened face of the groove 2.

What I claim as my invention is:—

A match striker comprising a striking plate having a centrally located lengthwise extending channel pressed therein and with the face of the channel roughened for contact with the match, eyes formed at the upper end of the plate by transversely doubly slitting the plate and pressing the intervening strip backwardly, a pair of pockets located at the lower end of the plate 40 alined vertically with the eyes and formed by slitting the plate and depressing the body of the plate backwardly at the slit, a fastening pin presenting a cross head and two parallel pointed prongs and having the 45 prongs passing slidably through the eyes and with their lower ends received within the pockets and a hump located at the upper end of the plate and positioned normally above the cross head of the pin.

Signed at Winnipeg, this 18 day of January 1918.

FRANKLIN FORD PETERS.

In the presence of—

GERALD S. ROXBAUGH,

K. B. WAKEFIELD.
